UNITED STATES PATENT OFFICE.

CHARLES R. BRYSON, OF PITTSBURGH, PENNSYLVANIA.

METAL-FORMING PRESS.

1,130,254.

Specification of Letters Patent. Patented Mar. 2, 1915.

Application filed April 8, 1914. Serial No. 830,328.

To all whom it may concern:

Be it known that I, CHARLES R. BRYSON, a citizen of the United States, residing at Pittsburgh, in the county of Allegheny and State of Pennsylvania, have invented a certain new and useful Improvement in Metal-Forming Presses, of which the following is a specification.

My invention, hereinafter disclosed, aims 10 to overcome a certain well known defect now prevalent in the art of metal working, or more particularly to that special class or branch dealing with the formation of various shapes of metal by the aid of a forging press, hydraulic or otherwise.

In the present well known methods of shaping the metal by pressure practically all standard types utilize a stationary base positioned directly underneath and in the 20 path of the reciprocally actuated press-head, which base carries the lowermost forming die.

The trouble now existing, and which I aim to eliminate by this invention, is due to 25 the fact that the forging, subsequent to receiving the required number of impacts from the presshead, becomes tightly wedged owing to the natural spread of the metal, in the lower immovable die member, necessitating additional mechanism, of variable 30 and expensive detail constructions, intended to overcome or minimize this objection. Additional power is required in order to operate these auxiliary mechanisms, which 35 naturally means added cost in the first place, and likewise greater expense of maintenance and operation.

As previously stated this invention is designed for the purpose of eliminating the 40 disadvantage of having the forging "stick" in the die, by providing a simple mechanism that can easily be incorporated with any of the well known styles of metal shaping presses, and I intend to accomplish this 45 object by means of the construction shown in the accompanying drawings and set forth in detail in the following specification, which involves one embodiment of my basic idea, but I reserve the right to make any 50 necessary alterations or amendments thereto that will conform in all respects to the

original intention, and which will be within the scope of the appended claims.

My basic idea therefore consists in substituting a movable die carrying member 55 for the stationary die block at present in common usage, which movable die, for all practical purposes and general utility, I propose to adequately mount for rotation beneath the vertically actuated and reciprocating presshead carrying the uppermost forming die.

In the drawing Figure 1 is an elevation of a common type of press equipped with my invention: Fig. 2 shows an end elevation of the same: Fig. 3 is a cross section of the rotatable die carrying member involving a plurality of bearing surfaces, the presshead being in working contact with the forging, showing a portion of the bar 70 already formed: Fig. 4 is a similar view showing the presshead away from engagement with the forging ready to finish its downward stroke and complete an additional segment of the bar, and Fig. 5 shows 75 a partially completed bar in perspective.

The principal detail construction of my invention resides in a suitable rotary die carrying member, designated as a whole by the numeral 1; which said member is of a 80 roll formation involving shaft portions and is adequately mounted directly underneath the vertical path of the reciprocating presshead 2, journals 3 being provided intermediate of the guide columns 4, thereby 85 properly supporting said rotary die member. The outer extremities or shaft portions of this movable die project a predetermined distance out from the guide columns, and have keyed, or otherwise secured 90 thereto, pinions or gears 5, one at each side as shown. The central portion of this rotary die is provided with an enlarged diameter of a roll-like formation, which, at the approximate longitudinal center, has 95 one or more circumferential grooves 6, of any suitable uniform depth and width, designed to receive and accommodate the forging. The two side walls of this groove are made with a predetermined degree of taper, 100 or in other words beveled, as shown in Fig. 1. The bottom surface of this groove 6 is

divided circumferentially into a plurality of independent tangentially arranged bearing surfaces 7, all of which may be identical in size and configuration, or they may be varied in accordance with the shape of the forging intended to be produced. The uniform detail of these surfaces 7 is clearly shown in one instance in the cross sectional view Fig. 4. It will readily be understood that these die or bearing surfaces are capable of a multiplicity of modifications to suit the various forms of forgings intended to be produced, but each roll 1 will have its own individual die forming surfaces.

15 The bar 8 to be shaped is placed, or fed in any suitable manner, into the groove 6, said bar being retained and seated on one of the surfaces 7 in a level or horizontal attitude, as shown. The first impact of the 20 presshead 2, carrying the top die piece, will spread and elongate the bar, forming a segment thereof into the shape desired. Said head is then raised from its pressing attitude in the groove 6 clear of the roll die 25 1, thus permitting free unimpeded rotation of said member in order to present in sequence a new lower die or forming surface each time the presshead descends. The beveled side walls provided in the groove 6 30 will afford ample means for a positive frictional release of the already forged segment, incidental to the rotation of the roll die 1.

The automatic and intermittent rotation of the member 1, and consecutive presentation of the die surfaces 7 each time the presshead rises, is brought about by the following described additional mechanism: Positioned at each end of the roll 1, adjacent to the rotary path of the pinions 5, 35 and designed for reciprocal perpendicular movement, are the operating bars 9, suitably housed by guides 10. The upper extremities of each of these said bars is provided with an in-turned or bent portion 40 11, which said bent portions are designed to be engaged by the guide collars 12, on the upward stroke of the presshead, for the purpose of raising said bars. Each of these 45 said bar members 9 carries in its lower portion a gravity actuated pawl 13, of adequate size and strength, which engages in the teeth of the adjacent pinion 5.

Fig. 1 illustrates the relative positions assumed by the coacting elements when the 50 presshead is lowered to its limit of downward movement, with the forging pressed into shape. On the upward stroke the presshead rises clear of contact with the rotary path of the roll die member 1, and, 55 at a predetermined point on this upward stroke, the guide collars 12 engage the bent portions 11 and lift the bars 9 simultaneously a distance determined by the limit 60 of the upward stroke. The instant said bars

begin their upward movement the pawls 65 13 engage in the teeth of the pinions 5, and, as this upward stroke continues, the die roll 1 is made to rotate a sufficient distance to bring the next succeeding die surface 7 into accurate horizontal alinement, 70 ready for the next downward stroke of the presshead. As said head descends the bars 9 also fall by gravity in unison with the movement of the guide collars 12, during which action the pawls 13, being pivotally 75 mounted in said bars, ride freely over the pinions 5, and when the said bars 9 reach their lowermost limit of movement said pawls will drop to a seat 14, and assume an approximate horizontal attitude, ready to 80 engage the pinions and rotate the die roll on the next succeeding upward stroke of the presshead. In this manner a succession of die surfaces are presented to the action of the plunger presshead at every downward stroke, with the exception that, owing to the normal distance intervening between the collars 12 and bent portion 11 of the bars 9, the presshead is capable of being operated up and down, within a limited 85 90 path, without affecting or disturbing the position of the rotary die 1.

Directly underneath the center of the rotary die member is positioned a fixed block 15, which is designed to assist in carrying 95 the weight of said roll 1, and take up the greater portion of the strain incidental to the pressing action of the head 2. The roll 1 seats directly on and contacts with said block 15 during the said pressing operation, 100 but owing to the fact that said roll is obliged to rotate, the contact between these two members 1 and 15 is sufficiently relieved on the upward stroke of the head 2, by providing compression springs 16 in the housings 3, which springs carry the weight of the roll, being depressed, when the head 2 is performing its work, and expanding sufficiently to permit clearance between the roll die and block when said head is raised. 105 This vertical oscillating movement given to the die roll by means of said springs 16 will be slight, not necessarily over one eighth of an inch play, but adequate to permit rotation of said die roll without interference from said block 15. 110 115

What I claim as my invention is:

1. In combination with a reciprocally actuated presshead, a forming member mounted for rotation in the path of the presshead, said forming member involving a circumferential groove having inclined side walls, the bottom of said groove being divided into a plurality of tangentially arranged working surfaces. 120
2. In combination with a reciprocally actuated presshead, a lower disposed forming die member mounted for intermittent

rotation in the path of the presshead, said
rotatable die member being provided with
a circumferential groove having inclined
side walls, the bottom of said groove being
5 divided into a plurality of tangentially ar-
ranged working surfaces, and automatic
means for turning said die member during
the upward stroke of the presshead to pre-

sent in sequence said working surfaces in
horizontal attitude.

In testimony whereof I affix my signature
in the presence of two witnesses.

CHARLES R. BRYSON.
